UNITED STATES PATENT OFFICE.

MAURICE W. LEWIS, OF CLOVER, VIRGINIA.

SAND-GUARD.

1,090,078.

Specification of Letters Patent. Patented Mar. 10, 1914.

Application filed May 27, 1913. Serial No. 770,211.

To all whom it may concern:

Be it known that I, MAURICE W. LEWIS, a citizen of the United States, residing at Clover, in the county of Halifax and State 5 of Virginia, have invented new and useful Improvements in Sand-Guards, of which the following is a specification.

This invention relates to sand guards for vehicles, and it has for its object to simplify 10 and improve the construction and operation of this class of devices.

A special object of the invention is to produce a simple and efficient guard consisting of a single piece of metal including a guard 15 plate and a shank, the latter being adapted to be mounted and secured by means of a clip upon the axle of a vehicle, and the former being adapted to overhang the hub and to deflect sand and mud from the same 20 and prevent its admission to the axle box; the device being capable of being applied to a vehicle without removing the wheel.

A further object of the invention is to combine with the sand guard proper a rotary 25 annular member detachably connected with the vehicle wheel for the purpose of deflecting sand and dirt upon the guard to be carried off by the latter.

With these and other ends in view which 30 will readily appear as the nature of the invention is better understood, the same consists in the improved construction and novel arrangement and combination of parts which will be hereinafter fully described 35 and particularly pointed out in the claims.

In the accompanying drawing has been illustrated a simple and preferred form of the invention, it being, however, understood that no limitation is necessarily made to the 40 precise structural details therein exhibited, but that changes, alterations and modifications within the scope of the claims may be resorted to when desired.

In the drawing,—Figure 1 is a perspective view of the improved sand guard, detached. Fig. 2 is a side elevation, partly in section, showing the sand guard applied in position for operation. Fig. 3 is a transverse sectional view taken on the line 3—3 50 in Fig. 2.

Corresponding parts in the several figures are denoted by like characters of reference.

The improved sand guard consists of a

metallic plate or blade 5, the same being bent to arcuate shape and to form outstanding ribs or flanges 6 along the longitudinal edges thereof. The blade 5 is provided with a longitudinal reinforcing rib 7 which is extended beyond one end of the blade to form a shank 8. The shank is bent to form an offset 9 adjacent to the blade, whereby the latter is elevated slightly above the shank. The shank 8 is provided in the underside thereof with a groove or depression 10 approximating the contour of the axle tree 11 of the vehicle to which the device is to be applied. The shank is also provided with an upturned lip 12 at the outer end thereof and with an upstanding lug 13 which is suitably spaced from said lip to admit therebetween the clip 14 by means of which the device is mounted in position for operation.

16 designates an annular band having radially extending lugs or arms 17, arranged in pairs at diametrically opposite 75 sides, for the reception of fastening members, such as suitably constructed bolts 18, whereby the band 16 is secured on the wheel encircling the hub, the bolts 18 passing between the spokes 19, as clearly seen in Figs. 80 2 and 3.

In the operation of this device, the shank 8 is placed on top of the axle tree in such a position that the blade 5 will overhang the inner end of the hub 15 within the annular 85 band 16, the shank being connected securely with the axle by means of the single clip 14. It is evident that the device may be applied or detached without disturbing the wheel, and it is, furthermore, evident that sand and 90 mud will be deflected by the ring or band 16 on to the blade 5 and by the latter on to the ground away from the hub, the flanges 6 serving to throw the dirt in an outward direction and positively preventing its ad- 95 mission to the axle box.

Having thus described the invention, what is claimed as new, is:—

1. In a sand guard for vehicles, an arcuate plate provided with outstanding flanges 100 along the longitudinal edges thereof, said plate being provided with a longitudinal reinforcing rib extended to form a shank, said shank having a longitudinal groove in the underside thereof, an upstanding terminal 105 lip, and an upstanding lug spaced from said

lip; in combination with a clip fitted between said lug and lip to secure the device in position for operation on a vehicle axle.

2. In a sand guard for vehicles, an arcuate plate provided with outstanding flanges along the longitudinal edges thereof, said plate being provided with a shank, and a clip for securing the shank on a vehicle axle; in combination with a ring or band

detachably mounted on the wheel and extending over the outer end of the arcuate plate.

In testimony whereof I affix my signature in presence of two witnesses.

MAURICE W. LEWIS.
